[57] **CLAIM**

The ornamental design for a video camera with liquid crystal monitor and video tape recorder, as shown and described.

DESCRIPTION

FIG. 1 is a perspective view of the top, front and right side of a video camera with liquid crystal monitor and video tape recorder with the upper portion pivoted to a horizontal front facing position showing my new design;

FIG. 2 is a perspective view of the top, rear and left side thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a perspective view similar to FIG. 1 with the upper portion pivoted to a vertical position thereof; and,

FIG. 10 is a perspective view similar to FIG. 2 with the top portion pivoted to a horizontal rear facing position thereof.

*FIG. 1**FIG. 2**FIG. 3**FIG. 4**FIG. 5**FIG. 6**FIG. 7**FIG. 8**FIG. 9**FIG. 10*
